UNITED STATES PATENT OFFICE.

WILLIAM H. DAY AND SAMUEL S. DAY, OF ROGANVILLE, TEXAS.

TIE.

1,291,776.

Specification of Letters Patent.

Patented Jan. 21, 1919.

Application filed December 31, 1917. Serial No. 209,780.

To all whom it may concern:

Be it known that we, WILLIAM H. DAY and SAMUEL S. DAY, citizens of the United States, residing at Roganville, in the county 5 of Jasper and State of Texas, have invented a new and useful Tie, of which the following is a specification.

This invention has reference to ties, and its object is to provide a device whereby 10 bundles of various kinds may be expeditiously tied or untied without wastage of cord and in materially less time than is employed in tying a bundle in the ordinary manner.

15 The invention comprises an elongated plate, preferably of metal, with a cord or string fast at one end, and the other end of the plate being recessed, curved and notched, and the plate at an intermediate 20 point being provided with a stud, whereby the cord may be wrapped about a bundle and about the stud, and then carried beneath the plate in a manner to effectively secure the cord with a minimum number of motions.

25 The invention will be best understood from a consideration of the following detailed description, taken in connection with the accompanying drawings forming part of this specification, with the further under- 30 standing that while the drawings show a practical form of the invention, the latter is not confined to any strict conformity with the showing of the drawings but may be changed and modified so long as such

35 changes and modifications come within the scope of the appended claims.

In the drawings:—

Figure 1 is a perspective view of a bundle of letters secured together by the tie of the 40 invention;

Fig. 2 is a longitudinal section of the tie and bundle of Fig. 1, with the section taken a short distance to one side of the longitudinal center line of the arrangement of 45 Fig. 1;

Figs. 3 to 6 are plan views with the stud in cross section, showing different steps in applying the tie.

Referring to the drawings, there is shown

50 an elongated and substantially rectangular plate 1, such particular shape, however, not being obligatory. The plate 1 is or may be curved slightly in the direction of its length, since most bundles when tied bulge more or less. The plate may conveniently be made 55 of sheet aluminum of sufficiently heavy gage,

such metal being strong and light, and as the plates may be used repeatedly, the cost of the metal is not material.

At one end, the plate 1 is provided with 60 a perforation 2 to which is secured one end of a cord 3 by tying the cord through the perforation in the form of a knot 4. Of course, any other means of securing the cord to the plate may be employed. Close to the 65 perforation 2 the plate 1 has a hole 5 formed therethrough, this constituting a convenient means for hanging up the plate when not in use.

That end of the plate 1 remote from the 70 perforation 2 is provided with a longitudinally extended entering recess 6 which may be somewhat less in length than one-half the length of the plate 1. The end of the plate into which the recess 6 enters and on opposite sides of the slot has bent portions 7 on one side of the general plane of the plate. One edge of the plate 1 at a point about opposite the inner end of the recess 6 is provided with a notch 8. In line with the recess 6 and between its inner end and the hole 5 and located about midway of the length of the plate is a headed stud 9 rising from the bulging face of the plate. If, now, the plate 1 be applied upon one face of a bundle 80 10, which may be considered as a bundle of letters, the stud 9 will be on that face of the plate remote from the bundle, and the bent ends 7 will be in spaced relation to the face of the bundle to which the plate is applied. 85 90

The cord 3, which may be considered as loose otherwise than where connected to the plate, is carried about the adjacent end of the bundle, along that face of the bundle remote from the plate, and back about the 95 other end of the bundle toward the stud 9, the cord extending lengthwise through the recess 6. The cord is carried about the stud 9 to the extent of about a quarter turn, and then around one side of the bundle, underneath the latter and back to the stud 9 about the other side of the bundle, but is carried about the stud in a direction opposite to the part of the cord first carried about the stud. The cord, after finally leaving the stud, is 100 105 slipped under the raised or bent ends 7 and forced underneath the plate, and carried along under the plate but over the first laid portion of the cord where traversing the recess 6 until the cord enters the notch 8 110 and confines that portion of the cord extending through the recess 6 against the in-

2
ner end of the recess. The friction is sufficient to hold the cord against any tendency of the expansive force of the bundle to pull the cord loose.

5 The tying of the bundle is very expeditiously performed, since it merely requires two movements to wrap the cord in opposite directions about the bundle, a turn about the stud 9 and a single movement carrying 10 the cord beneath the raised or bent ends 7 until movement is stopped by the recess 8 and that portion of the cord within the recess 6 at the inner end thereof.

In the foregoing description, the term 15 cord as applied to the member 3 is to be understood as covering any suitable member answering the purpose for which the cord is used. The term plate as referring to the member 1 is to be considered as covering 20 any suitable sheet, preferably a metal sheet, whether of aluminum or other material. That end of the plate or body member 1 divided into two parts by the recess 6 and terminating in the bent extremity 7 may 25 be considered as formed of two fingers spaced apart by the recess 6 sufficiently to freely receive the cord 3. The stud 9 may be formed in any suitable manner, and need not be constructed as shown, although the 30 headed stud answers the purposes of the invention.

What is claimed is:

1. A tie for packages comprising a plate having an entering recess at one end dividing said end into two substantially parallel fingers with the extremities bent to one side

2. Copies of this patent may be obtained for five cents each, by addressing the "Commissioner of Patents, Washington, D. C."

of the general plane of the plate, a stud between the fingers and the other end of the plate on the same face of the plate as the bent ends of the fingers, and a cord adapted 40 to be attached to the end of the plate remote from the fingers.

2. A tie for packages comprising a plate having an entering recess at one end dividing said end into two substantially parallel 45 fingers with the extremities bent to one side of the general plane of the plate, a stud between the fingers and the other end of the plate on the same face of the plate as the bent ends of the fingers, and a cord adapted 50 to be attached to the end of the plate remote from the fingers, one of the fingers having a notch in its outer edge adjacent to the inner end of the recess.

3. A tie for packages comprising an elongated plate with a cord adapted to be attached to one end of the plate, said plate being provided with an intermediate stud constituting a direction-changing element for the cord, and around which the cord is 55 passed, and a longitudinally disposed entering recess at the other end of the plate, said recess being of a width to freely receive the cord lengthwise.

In testimony that we claim the foregoing 60 as our own, we have hereto affixed our signatures in the presence of two witnesses:

WILL H. DAY.
SAM. S. DAY.
